RUFUS WRIGHT, OF BROOKLYN, NEW YORK.

Letters Patent No. 77,561, dated May 5, 1868.

IMPROVED CHERRY-STONER.

The Schedule referred to in these Letters Patent and making part of the same.

TO ALL WHOM IT MAY CONCERN:

Be it known that I, RUFUS WRIGHT, of Brooklyn, in the county of Kings, and State of New York, have invented a new and improved Machine for Stoning Cherries; and I do hereby declare that the following is a full, clear, and exact description thereof, which will enable others skilled in the art to make and use the same, reference being had to the accompanying drawings, forming part of this specification.

This invention relates to a new and improved machine for removing the stones from cherries; and it consists in the employment or use of an intermittently-rotating feed-wheel, and in means for operating the same, and also in certain means for insuring the feeding of but one cherry at a time to the stone-ejecting apparatus, all being constructed and arranged as hereinafter set forth, whereby a very simple and efficient apparatus for the purpose specified is obtained.

In the accompanying sheet of drawings—

Figure 1 is a side sectional view of my invention, taken in the line *x x*, fig. 2.

Figure 2, a horizontal section of the same, taken in the line *y y*, fig. 1.

Figure 3, a detached inverted plan of a lever pertaining to the same.

Similar letters of reference indicate corresponding parts.

A represents the base of the machine, to one end of which a lever, B, is attached by a hinge or joint, *a*. This lever has an oblong slot, *b*, made in it, near its free or disengaged end, and to the under side of the lever, beyond the outer end of the slot, there is a pendent projection, *c*, the object of which will be presently seen.

C represents a wheel, which has four (more or less) holes *d*, made through it near its periphery. This wheel is fitted loosely on a rod, *e*, which passes through the base, A, and to the upper end of the rod *e* there is attached a vertical flat plate, D, the upper part of which is made in spiral form, as shown at *f*. This plate D passes through a slot, *g*, in a metal plate, *h*, which is attached to the under side of the lever B, below the slot *b*. On the rod *e*, at the inner end of the plate D, there is a ratchet, E, provided with four teeth *i*, or as many teeth as there are holes *d* in the wheel C, and to the upper surface of the wheel C there is attached a pawl, F, against which the teeth *i* of the ratchet catch.

G represents a series of needles, which are attached to the under side of the lever, in line with the path of rotation of the holes *d*, and H is an angular metal plate, which is attached to the base, A, and projects over the rear part of the wheel, the portion which projects or extends over the wheel being slotted longitudinally, as shown at *j* in fig. 2.

I represents a hopper, which is attached to a fixture, J, at one side of the base, A, the lower end of which said hopper being just above the upper surface of the wheel C. K is a yoke or band, which is fitted on the lower end of the hopper, and is connected thereto by a joint, *k*, so that the part opposite to said joint, and which rests on the upper surface of wheel C, may rise and fall freely.

The operation is as follows:

The cherries may be fed into the hopper I through any proper spout or trough, it not being designed that the hopper shall hold more than two cherries, in order to avoid superincumbent weight. The holes *d* in the wheel C are designed to be sufficiently large to receive the largest-sized cherries, but not large enough to receive two small ones, the largest portion of the uppermost small cherry to be above the level of the wheel C.

Each time the lever B is raised, the plate D will be turned, owing to the spiral form of its upper part *f*, being fitted in the slot *g* of plate *h*, and the wheel is turned a quarter of a revolution each time said lever is raised, and a hole, *d*, with a cherry in it, is brought under the slotted upper part of the plate H.

Each time the lever B is forced down, the needles G penetrate the cherry in the hole *d*, underneath them, and force out the stone from the cherry through a hole, *h* in the base, A, the upper end of said hole serving to centre the cherry in the holes *d* of the wheel C.

As the lever B is drawn upward, the plate H prevents the cherry from rising with the needles, and the stoneless cherries drop out through a notch, *l*, in the front end of the base, as each hole *d* passes over said notch.

The yoke or band K, in case of two small cherries being in a hole, d, retains the top cherry, or prevents it from passing along in the hole with the lower one; and in case of one large cherry being in the hole, and projecting a trifle above it, the yoke or band will readily rise a little to allow it to pass, as the top of the cherry will press against K at its lower part, below the joint k, whereas the upper cherry of the small ones will press against K at too high a point to raise it.

The pendent projection e prevents the lever B being pressed down so far as to allow the points of the needles G to come in contact with the plate H or wheel C when a hole, d, is not in line with the needles, the projection e, in this case, striking the upper surface of the wheel C, in consequence of a hole, d, not being in line with it. By this means the needles are preserved from injury, in case the lever B is forced down before being fully raised, and the wheel C consequently not turned a full quarter of a revolution.

Having thus described my invention, what I claim as new, and desire to secure by Letters Patent, is—

1. The intermittently-rotating feed-wheel C, when operated by the lever B, or other device, which carries the stone-ejecting needles G, substantially as and for the purpose set forth.
2. The pendent projection or guard e, attached to the needle-bar or lever B, in connection with the intermittently-rotating feed-wheel C, for the purpose specified.
3. The yoke or band K, attached to the hopper I, in connection with the feed-wheel C, arranged to operate substantially as and for the purpose set forth.
4. The spiral plate D, ratchet E, pawl F, and the lever B, or its equivalent, for operating the wheel C, all arranged substantially as and for the purpose specified.

RUFUS WRIGHT.
